AMBROSE N. DIEHL AND SAMUEL G. WORTON, OF DUQUESNE, PENNSYLVANIA.

METHOD OF OPERATING REGENERATIVE FURNACES.

Application filed July 9, 1921. Serial No. 483,500.

This invention relates to the operation of regenerative furnaces and, while not restricted thereto, more particularly relates to the operation of regenerative open hearth furnaces used in the manufacture of steel and similar reducing and refining operations.

One object of our invention is the provision of a novel method of burning the gaseous fuel used in heating such regenerative furnaces, wherein light gases such as by-product coke oven gases may be employed without the aid or addition of tar or oil or other illuminants, and whereby complete combustion of the gases is obtained, the use of an excess of air is avoided in burning the gases, and the life of the roofs of such furnaces is materially lengthened.

Another object of our invention is to provide a novel method of burning light gases, such as debenzolized by-product coke oven gases, wherein the usual lack of luminosity in the flame of the burning gases is overcome, the gases are burned with a luminous flame, and whereby luminosity of the flame is regulated and controlled and, when desired, is prevented.

The above and various other objects and advantages will be more fully brought out in the following specification and will be illustrated in the accompanying drawings, in which—

Figure 1 is a sectional plan of an open hearth furnace adapted for use in carrying out our invention.

Figure 2 is a sectional elevation of the same, the section being taken on the line II-II of Figure 1.

Figure 3 is a plan showing on an enlarged scale, a preferred form of auxiliary gas burner by which a mixture of gas and air may be supplied to the furnace.

Referring now particularly to the drawings forming part of this specification, the numeral 2 designates the hearth of a regenerative open hearth furnace which is of the usual design. The furnace is provided with a central gas port 3 and two air ports 4 and 5 at each of the opposite ends of the furnace hearth. The ports are arranged in the same manner at each end of the hearth so it is to be understood that the description of one will apply to both ends.

The furnace shown by the drawings as

originally built was adapted for burning producer gas, and, therefore, the gas port 3 is connected at its rear end with a vertical flue 6 leading upwardly from a slag pocket 7, and the slag pocket is connected by a port 8 with a regenerator chamber 9, which in turn is connected by a flue 10 with a double valve casing 11 having a stack valve 12 and a gas valve 13 therein, the valve casing 11 being adapted to connect the flue 10 with either the stack flue 14 or producer gas flue 15, according to which of the valves 12 and 13 is raised into open position.

The valve casing 11 has manholes 16 which normally are open only to permit of inspection, for repairs, etc. of the valves 12 and 13, and interior of the valve casing, and which remain closed at other times. A new use is made of these manholes in connection with our invention, which will be more fully brought out later.

The gas flue 15 through which the gas is supplied to the furnace when burning producer gas is provided with a sand damper 17 for sealing the flue 15 when the furnace 80 is operated with by-product coke oven gas, this damper remaining in sealing position at all times when operating the furnace in accordance with this invention.

The air ports 4 and 5 are connected by flues 18 and 19 with a slag pocket 7^a running parallel with the slag pocket 7 for the gas port, and the slag pocket 7^a is connected at one end by the horizontal flue 20 with an air regenerator chamber 21, which in turn is connected by a horizontal flue 22 with the stack flue 23 leading to the stack 24. Each of the flues 22 is provided adjacent the end thereof communicating with the stack flue 23, with a sliding shutter or damper valve 25, so that one of the flues 22 may be cut off from the stack 24 when the end of the furnace with which such flue 22 connects is being used to supply fuel to the furnace hearth. It will, of course, be understood that the furnace being of the reversing type, at such time the other flues 22 and 10 will be used to conduct the products of combustion passing through the air ports 4 and 5 and gas port 3 of the outgoing end of the furnace to the stack 24.

Each of the two flues 22 is provided with an air inlet valve 26 which is adapted to be opened to admit air to the regenerator 21 when fuel is being supplied to its end of the

furnace, the valve 26 being open when the damper valve 25 is closed.

In adapting the above described furnace to carry out the method to be described, the 5 only changes made or necessary to make are that the sand dampers 17 are provided to close or seal the flues 15 so as to completely cut off the supply of producer gas, and that gas supply pipes 28, 29, and 29^a are provided 10 which lead from a suitable main and terminate in the tubes 30, 31 and 33 in the sides and end of the gas port 3, so as to deliver oppositely directed streams of gas across the width and also lengthwise of the gas port 15 3 and at right angles to the stream of air flowing to the furnace hearth through the port 3, and supplied thereto by the vertical flue 6, as referred to later.

The end inlets as shown comprise a tube 20 33 projecting through the furnace end wall into the port 3. The rear end of the burner tube 33 is telescoped over a gas supply tube 34 of less diameter, this smaller tube 34 having a nozzle or contracted outlet 35. The 25 tube 33 also is provided at its rear end with an air inlet opening 36, a slidable gate or shutter 37 being pivotally connected thereto so as to provide means for regulating and controlling the amount of air drawn into 30 the tube by the aspirating effect of the gas discharged from the nozzle 35. The gas supply pipe 29^a is connected to the same gas supply main as the pipes 28 and 29, and a valve is provided on the pipe 29^a as well 35 as on the pipes 28 and 29 to control, and shut off the gas supply.

The manholes 16 in the valve casings 11 have their usual covers removed, and a hinged cover plate 32 is substituted therefor. 40 The cover plate 32, which must be raised and lowered in connection with our improved method, is connected by a chain or other flexible connection 32' to a cross bar 34 secured to the gas valve 13, so that by 45 raising the gas valve 13 with its usual operating mechanism the cover 32 will be lifted to open the manholes to the atmosphere and permit inflow of air.

By properly adjusting the amount of lifting 50 movement of the cover plates 32, (through the medium of the chains 32') it is made possible for the luminosity of the flame in the furnace hearth to be regulated and controlled and prevented at will by manipulation of the gate or shutter 37 on the air inlet 36 of the combined gas and air inlet tube 33.

In the usual operation of the furnace when using producer gas, the gas valves 13 60 are lifted or opened when supplying gas to the incoming end of the furnace, and the same lifting operation is maintained in utilizing the present method, except that the gas valve itself has no function other than 65 as a medium to operate the cover plate 32,

since the producer gas main is sealed by the sand damper 17. Raising of the cover plate 32 will allow air to be drawn by suction through the manholes 16 into the flue 10, regenerator chamber 9, vertical flue 6, and into the gas port 3 where it mixes with the gases supplied to the combustion chamber through the gas supply pipes 30, 31, and 33.

Our improved method of heating the furnace with by-product coke oven gases will 75 now be set out in detail, it being expressly understood that the method is not limited to a furnace constructed in the precise manner set forth above, since different forms of furnaces and various arrangements of the ports may be devised for carrying out the method.

By product coke oven gases either washed or unwashed, are supplied to the furnace from a suitable main through the pipes 30, 31, and 33, which deliver the gases to the gas port 3. At the same time the cover plate 32 on the manhole 16 communicating with the flue 10 on the incoming end of the furnace allows air, in amounts insufficient to completely burn the gases to be drawn into the flue 10, and through the regenerator 9 (the regenerator ordinarily used to preheat producer gas) to the gas port 3. The air, which becomes heated in its passage through the regenerator, mixes with the gas entering the port 3, where ignition instantly begins. By adjusting the shutter 37 on the supply pipe 33 additional amounts of air may be obtained. The maximum luminosity of the flame is obtained when a mixture of air and gases having approximately 50 per cent of the theoretical volume of air required for complete combustion is drawn into the port 3 and becomes mixed with the gases supplied by the pipes 30, 31, and 33, the burning mixture passing to the nose of the port where the additional air needed for complete combustion is supplied, combustion of the gases being completed before the ports at the opposite or outgoing side of the furnace is reached. The amount of air entering the port 3 may be varied by adjusting the cover plate 32 or the gate or shutter 37, and in this manner means are provided whereby more or less luminosity may be obtained by increasing or decreasing the volume of air supplied to the port 3.

The mixture of air and gases is ignited in passing through the port 3, and combustion is partially completed by the time the burning mixture reaches the nose of the port and emerges into the furnace hearth 2. The temperature of the partly burned mixture within the port 3 is sufficiently high to partially decompose, within the port 3, the hydro-carbons present in the mixture and results in the splitting up of the same, with a resultant partial dissociation of the carbon and hydrogen. Air in amounts sufficient 120 to complete combustion of the mixture is 125 130

drawn through the air valve 26 in the flue 22, and after being heated in the air regenerator, passes through the air ports 4 and 5 into the hearth 2, where it mixes with the 5 partially burned gases issuing from the gas port 3. A secondary or complete combustion then takes place across the furnace hearth which is completed by the time the 10 gases reach the gas port 3 and air ports 4 and 5 on the outgoing end of the furnace, through which the products of combustion pass from the furnace.

Heretofore by-product coke oven gases, on account of the large hydrogen content 15 and consequent relatively low density have been considered unsatisfactory for use in regenerative furnaces, one reason being on account of the tendency of the flame to follow the furnace roof and thereby burn out 20 or quickly destroy the roof. The greatest difficulty in using by-product gases in open hearth regenerative furnaces has been the lack of control of the gases due to the absence of a luminous flame, which makes it 25 impossible to judge the flame temperature in the customary manner employed when burning either natural or producer gases. As it is possible with our improved method described above to produce a luminous flame 30 with by-product gases and to control the degree of luminosity, the difficulties in judging the flame temperatures are avoided and overcome. As the degree of combustion is controlled so that dissociation takes place 35 within the gas port 3 and later complete combustion occurs in the hearth, with a properly designed burner nozzle and port the gases can be directed upon the charge on the hearth of the furnace and away from the 40 furnace roof so that the roof difficulties heretofore encountered are eliminated.

As has been said before, the luminosity of the flame will vary with the amount of air introduced into the gases prior to the complete combustion thereof, so that when the 45 amount of air introduced or mixed with the gases in the port 3 is insufficient to completely burn the gases and the so-called mixture is only partly consumed while in the port, and is afterward completely consumed within the furnace, the resulting flame will be luminous. As the amount of air mixed with the gases in the port 3 is increased so will the luminosity of the result- 50 55 ing flame be proportionally lessened until when the amount of air entering the port 3

with the gases is sufficient to completely burn the gases, the resulting flame will be practically non-luminous. In other words when air is supplied to the port 3 with the gases 60 prior to the entrance of the mixture to the furnace hearth, the luminosity of the flame in the hearth will be increased in inverse proportion to the amount of air supplied to the port. 65

The many advantages of operating regenerative furnaces in accordance with our improved method will be apparent to those skilled in the art. By partly consuming the gases before they emerge into the furnace hearth, by-product coke oven gases can be broken up so as to provide a luminous flame and by regulating the amount of air supplied to the gases in the gas port, the luminosity of the flame may be accurately 70 75 controlled. Through the luminosity of the flame it is possible to accurately gauge the furnace temperatures, while a properly designed port directs the gases into the hearth so as to lengthen the life of the roof 80 with the consequent increased period of production of the furnace.

Various modifications of the above method and the apparatus used in carrying out the method may be made without departing 85 from the spirit of the invention as defined in the appended claim; for example, the air may be preheated or not, without materially affecting the operation of the invention, or the combustible gases may be other than 90 by-product coke oven gases and the number and type of gas supply pipes may be varied.

We claim:—

In the operation of regenerative furnaces, the method of firing furnaces with 95 by-product coke oven gas without the addition of illuminants, which consists in breaking up the hydro-carbons contained in the gas to be fired by mixing with the gas approximately fifty per cent of the amount 100 of preheated air necessary to support complete combustion and causing partial combustion of the mixture, then passing a stream of the mixture after partial combustion into the furnace, and supplying additional pre-heated air to the furnace hearth in quantities sufficient to support complete combustion of the mixture within the furnace. 105

In testimony whereof we have hereunto set our hands.

AMBROSE N. DIEHL.
SAMUEL G. WORTON.
